GARMENT-LIKE SLEEPING BAG

George C. Daiber, Seattle, Wash., now by judicial
change of name Ome Craig Daiber

Application September 25, 1935, Serial No. 42,102

3 Claims.

(Cl. 2—83)

My present invention relates to the art of outdoor sleeping equipment and more particularly to a garment-like sleeping bag.

Persons accustomed to camping and sleeping in the open have for many years used the so-called sleeping bag, instead of the more conventional bed made of blankets, quilts and the like. The reason for this is that a minimum weight of sleeping equipment provides the maximum warmth as there is no chance of the covers being disarranged and not providing uniform coverage throughout a person's body. One of the principal objections, however, to the sleeping bag has been that once a person has retired it is very difficult to get out of the bag again, and to, the average bag does not permit one to move around after awakening so that full circulation can be restored before getting entirely out of the bag to dress. This is not particularly discomforting to the summer camper but is a matter of some concern to the person using a sleeping bag in high altitudes and in cold weather.

With my present sleeping bag I have provided sleeve-like and trouser-like portions so that a person may walk around in the garment-like bag and have the use of his hands which can be extended outside of the sleeping-bag so that for limited use the bag is in all intents a sleeping garment. With the bag so constructed it is possible, where the weather is cold, for the user to don the bag in the early evening and sit within the circle of the camp fire and have the full protection from the weather that even the heaviest of clothing would not afford him. Further, it is possible to arise during the night, replenish wood on a fire, or investigate possible vermin about camp and, when morning comes, a new fire can be built without having to get out of the sleeping bag thus exposing the user to the elements.

Further, my garment-like sleeping bag provides an excellent means for protecting still hunters, such as duck, geese and game hunters who may stand on watch during the night or early morning hours.

A still further use is to provide a comfortable traveling garment for dog and stage users in the cold climates, particularly for persons who are ill or injured.

A further object is to provide a sleeping bag in which the sleeper may turn to rest on his side and still have it optional whether or not the bag turns with him or he turns over inside

Other and more specific objects will be apparent from the following description taken in connection with the accompanying drawings, wherein

Figure 1 is a plan view of my sleeping bag, certain parts being broken away and shown in section to better illustrate the construction thereof.

Figure 2 is a cross-sectional view, in perspective, taken substantially along the lines 2—2 of Figure 1.

Figure 3 illustrates my sleeping bag as it would be used if the wearer decided to use it as a garment, while walking about.

Figure 4 is a plan view showing my sleeping bag as it is used for protection of the user while sleeping.

Referring to the drawings, throughout which like reference characters indicate like parts, 6 designates the outer covering of my bag. This may be of any material that has proved suitable for bag covering. It may range from the porous duck or twill materials to the various types of water-proof material, in accordance with the use to which the bag is to be put and the personal inclination of the user. Disposed inside of covering 6 is a, preferably, down filled bag 8. This is usually composed of an outer covering 9 and an inner covering 10 between which down, wool or other filling 12 is provided. The two coverings 9 and 10 are quilted together in some one of the proved manners used in sleeping bag construction. For some uses it may be desirable to use merely an inner bag made of blanketing wool or fleece materials, or as quite often occurs in extreme temperatures, it may be most desirable to have a down bag and then to have inside of the same a fleece or wool bag.

The outstanding feature of my present bag resides in its garment like construction, in that it is provided with a hood portion 14, having 40 puckering strings 16 so that the face opening 11 may be enlarged or reduced. In some cases it may be found desirable to have the same lined or edged with fur. A body portion 18 is next provided of such a size as to fit the user very loosely. This is in turn provided with sleeve-like extensions as 20 and 21 which in turn terminate in an adjustably fastened wrist, or cuff, member 22 formed on the outer covering 6. The 50 inner garment terminates in a, preferably, knitted wrister 24. Both cuff 22 and wrister 24 are so arranged that when the sleeper withdraws his hand a complete closure is formed for the sleeve so that no air will be admitted. The sleeves 8

should be longer than the arms with the hands extended.

The sleeves, themselves, are really more extensions of the bag than sleeves, in that their depth at the shoulder is very great so that the user can withdraw the hand after he has lain down and, by folding the arm up after the showing of Figure 4, the entire arm can be withdrawn from the arm portion of the bag.

The lower end of body 18 is provided with very short leg portions as 26 and 27. These leg portions are so short as to be hardly classified as legs. They normally reach only about half way up to the knee. Their main purpose is to provide for the foot reinforcement members as 29 and 30. This reinforcement may be made of the same material that the outer covering 6 is made from or they may, preferably, be made from more wear resistant material as light leather or rubber for instance. The leg portions should be fully cut and have ample breadth so that there will be sufficient room for placing the feet in, and withdrawing them from the same; the foot portions should be of sufficient length to allow the placing of both feet in a single leg after the showing of Figure 4 so that the user may have the increased warmth acquired when the two feet are together in sleeping.

When the bag is to be used as a garment so that the wearer can move about, it is normally desirable to tie the leg portions above the ankle after the showing of Figure 3 and to this end I have provided tapes, or cords 32 and reinforcement pieces as 34 secured one to each leg portion in a position corresponding to the counter of a shoe, except that the same are of much greater extent.

To further facilitate the use of the bag as a garment it should, preferably, be provided with a belt, or tape, as 35 so that the bag can be made to fit, to a degree at least, about the user's waist. It has been found convenient to provide the sleeping bag with pockets on the outside as indicated at 37 and 38 and on the inside of the garment so that it may be used at night. These latter are not shown in the drawings, but would normally lie substantially under pocket 37 or 38, possibly a little lower down so as to be more readily available.

To make it convenient to get in and out of the bag and also to render it more useable as a night garment, I have provided closure members of the locking lug type, so arranged that they may be opened or closed from the inside as well as from the outside; it being necessary to use two of these, an inner one 40 for the inner bag 8 and an outer one 41 for the outer bag. In addition to the lug fasteners I have found it desirable to provide the usual snap fasteners as indicated at 42 and 43 so that added protection will be given

to the seams and also that a method of closure for the garment will be provided in case of any mal-functioning of the lug fasteners. After the front of the garment has been closed I then provide an additional snap fastener as 45 for holding 5 in place the flap 46 of hood 14.

The foregoing description and the accompanying drawings are believed to clearly disclose a preferred embodiment of my invention but it will be understood that this disclosure is merely 10 illustrative and that such changes in the invention may be made as are fairly within the scope and spirit of the following claims.

Having thus fully described my invention, what I claim as new and desire to secure by Letters 15 Patent is:—

1. An interchangeable sleeping bag and garment comprising inner and outer layers throughout the garment and having a body, sleeves and hood, said body formed with short leg portions of 20 substantial width adapted to loosely enclose a foot, said sleeve portions formed on said body and having bases extending from the hood to the waistline, closed shoe portions on said leg portions for garment use, means for securing the shoe 25 portions, aligned openings through the layers of the body portion, means for closing the inner opening from the inside of the inner layer, and means for closing the outer opening from the 30 outside of the garment.

2. An interchangeable sleeping bag and garment comprising inner and outer layers throughout the garment and having a body, sleeves and hood, said body formed with short leg portions of substantial width adapted to loosely enclose 35 a foot, said sleeve portions formed on said body and having bases extending from the hood to the waistline, closed shoe portions on said leg portions for garment use, means for securing the shoe portions, openings through the layers of 40 the body portion, means for closing the inner opening from the inside of the inner layer, and means for closing the outer opening from the outside of the garment.

3. An interchangeable sleeping bag and garment having a body, sleeves, and hood, said body and hood comprising inner and outer layers, said body formed with short leg portions of substantial width adapted to loosely enclose a foot, said 45 sleeve portions formed on said body and having bases extending from the hood to the waistline, closed shoe portions on said leg portions for garment use, means for securing the shoe portions, openings through the layers of the body portion, 50 means for closing the inner opening from the inside of the inner layer, and means for closing the outer opening from the outside of the garment.
